LOW-TEMPERATURE CABINET
CONSTRUCTION

Robert D. West, and William U. Vinton, Manitowoc, Wis., assignors to Manitowoc Shipbuilding Company, Manitowoc, Wis.

Application April 28, 1944, Serial No. 533,127

6 Claims. (Cl. 62—99)

This invention relates to a low temperature cabinet construction and is particularly directed to a cabinet for quickly freezing and storing frozen foods.

In low temperature cabinets it has been found that although the top, bottom, side and back walls of the low temperature cabinet may be adequately insulated, a considerable loss or transfer of heat occurs around the door. While this is true in ordinary domestic refrigerators where the temperatures are moderately low, it is even more pronounced in very low temperature cabinets, such as those for quick freezing and frozen food storage purposes.

This invention is designed to overcome the above noted defects, and objects of this invention are to provide a novel form of low temperature cabinet which is so constructed that a front door is provided for the entire cabinet to thus provide the major sealing of the cabinet on its front side, and which also is provided with a plurality of drawers so arranged that each drawer substantially seals its portion of the cabinet behind the door and thus provides an additional seal.

Further objects are to provide a low temperature cabinet having interchangeable drawers and having evaporator units or evaporator plates positioned above each drawer and positioned below certain of the drawers, the evaporator plates being of different capacities so that different temperatures may be maintained in different drawers, for example, with the upper drawer maintained at a very low temperature for quick freezing purposes and with the lower drawers maintained well below freezing for the storage of frozen foods after they have been quickly frozen in the upper drawer, the interchangeability of the drawers permitting the drawer in which the quick freezing has taken place to be substituted for an empty drawer which is placed in the space formerly occupied by the quick freezing drawer, thus always maintaining the low temperature cabinet for the quick freezing of a subsequent batch of foods.

Further objects are to provide a novel form of low temperature cabinet in which the drawers are so constructed that they are imperforate with regard to their sides, front, back and bottom and will thus hold the dense chilled air within the drawer even though the drawer is pulled outwardly, so that the minimum loss occurs even when it is desired to place food within or remove food from a drawer, the construction also being such that when a drawer is pulled out and warm air fills the space behind the partially withdrawn drawer, this warm air is again discharged when

the drawer is pushed back into place substantially without disturbing the temperature of other portions of the low temperature cabinet.

A further object is to provide a low temperature cabinet which is so arranged that the drawers are spaced from the evaporator units or evaporator plates and are not in direct contact therewith, thereby avoiding any chance of the drawers freezing tight to the adjacent evaporator plates.

Further objects are to provide a low temperature cabinet which is adapted for quick freezing and storage of frozen foods, which is so made that it may be formed not only in relatively large units but may be formed and economically operated in relatively small units so that it is well adapted for domestic use.

Embodiments of the invention are shown in the accompanying drawings, in which:

Figure 1 is a vertical sectional view through the low temperature cabinet, such view corresponding to a section on the line 1—1 of Figure 3.

Figure 2 is a vertical sectional view at right angles to Figure 1, such view corresponding to a section on the line 2—2 of Figure 3.

Figure 3 is a sectional view on the line 3—3 of Figure 2.

Figure 4 is a fragmentary detail of a modified form of the invention.

Figure 5 is a sectional view on the line 5—5 of Figure 6.

Figure 6 is a view looking downwardly on the lower portion of the inner cabinet.

Figure 7 is a front view of the structure shown in Figure 5.

Figure 8 is a sectional view on the line 8—8 of Figure 5.

Referring to the drawings, it will be seen that the low temperature cabinet comprises an inner casing 1 and an outer casing 2 between which insulating material 3, such as fiber glass, is positioned. The inner and outer casings are connected by means of breaker strips 4 and 5 which are shown most clearly in Figure 4. These breaker strips interlock with flanged marginal portions of the inner and outer casings. They are formed of thermally insulating material and the joints between the breaker strips and the casings are sealed by means of a suitable asphaltic compound

50 which is odorless, water repellent and non-absorbent and has heat insulating characteristics. The material commonly known as "Hydrolene" has been successfully employed. The inner and outer casings interlock with the inner breaker strip 4 and the breaker strip 5 interlocks with

the inner and outer casings also and serves as a wedging member to maintain the interlocking relation between the breaker strips and the inner and outer casings. The particular construction of breaker strips and interlocking joints forms the subject matter of the copending application of Robert D. West and Alvin N. Dedricks, for Low temperature cabinet constructions, Serial No. 533,126, filed April 28, 1944.

A main door 6 is hinged as indicated at 7 to the outer casing and may be temporarily locked as indicated at 8 and is suitably insulated and provided with a sealing gasket 9 adapted to form an air-tight seal with the cabinet when the door is closed in accordance with the usual construction. The inner casing 1 is provided with a plurality of channel members 10 at spaced intervals along its side walls and is provided with L-shaped members 11 at its lower corners. A plurality of drawers indicated at 12 are slidably mounted on the upper side of the channel members and on the L-shaped members 11 and are adapted to be slid inwardly and outwardly as desired when the main door 6 is opened.

Each of the channels 10 carries a supporting bar 13 of thermally insulating material upon which the flanged edges of evaporator plates or units 14 rest. The evaporator plates or units may have their flanges secured to the bars 13 and the bars may in turn be secured to the channel members 10 in any suitable way, for instance as shown in Figure 3 by means of screws. It is to be noted from Figure 1 that transversely extending bars 15 extend crossways at the front of the cabinet and are supported at their ends by the channel members 10.

It is to be noted particularly that each of the drawers 12 is provided with a front portion 12' which has upper and lower extending edges which contact with the transverse bars 15 when the drawers are closed and the lowermost of which contacts with the front edge of the bottom of the inner casing 1 so as to prevent circulation of air outwardly from the interior of the inner casing in addition to the sealing provided by the main door 6.

The evaporator units or plates 14 are connected by means of a series of pipes 16 with the compressor and radiator units 17 and 18 respectively. These units are carried by a sub-base 19 which in turn rests on the bottom or base portion 20 of the cabinet and is removably secured thereto in any suitable manner not shown. It is to be noted that a rear portion 21 below the insulated part of the cabinet is open so that the air may freely circulate through the cooler 18 under the impetus of the fan 22, the compressor and the fan, of course, being controlled thermostatically in the usual manner. The lower front of the cabinet is closed by means of a removable member 23 provided with a plurality of air inlet slots 24, such member 23 being held in place in any suitable manner not shown.

The bottom of the inner casing 1 is provided with a depressed, approximately centrally located channel 25, see Figures 1, 2, 5 and 6, within which the horizontal portions of the pipes 16 are positioned. It is to be noted from reference to Figure 3 that the rear wall of the drawers 12 are inwardly depressed as indicated at 26 to provide clearance for the vertical portion of the pipes 16.

It is intended that the inner and outer casings 1 and 2 and the insulation therebetween be completely assembled and that thereafter a refrigerating system may be installed as a packaged

unit without dismantling any portion of the refrigerating machinery or unit. This is accomplished by providing means whereby the entire refrigerating units including the evaporator units 14, the pipes 16, and the power plant including the compressor, fan and radiator, may all be installed by merely slipping them in from the front. This is accomplished by providing a slotted portion in the bottom wall of the inner casing 1 and providing a block 27 of thermally insulating material with a downwardly slanting slotted portion 28 forming a continuation of the channel 25 as most clearly shown in Figures 1, 5, 6 and 8.

The downwardly slanting slot 28 in the block 27 extends downwardly completely through the block 27 and the block 27 is thus provided with a pair of forwardly projecting leg portions 27', see Figure 8. An upwardly slanting channel-shaped metal member 29 is positioned in the channel 28 of the block 27, as shown most clearly in Figure 8, and is secured to the block by means of screws or in any other suitable manner. A closure block 30 closes the channel in the member 28, see Figure 8, and has a portion that extends slightly downwardly into such depressed channel. It forms in effect a continuation of the breaker strips 5 which are on opposite sides thereof. It is secured to a finishing plate or front plate 31 which has a rearwardly and downwardly extending flanged portion 32, see Figure 5, fitting within a slot in the closure block 30, the closure block 30 being of thermally insulating material and forming, as stated, a continuation of the adjacent breaker strips 5. The front finishing plate 31 may be secured to the forwardly projecting arms 27' of the block 27 by means of screws 33 as shown in Figure 7. It is preferable to fill the upwardly slanting channel through which the pipes 16 pass with an asphaltic compound such as "Hydrolene."

It is thus possible to have the evaporator plates or units 14 and the compressor and radiator or cooler and fan and sub-base all shipped as a unit in their properly spaced relation and thereafter merely slip the parts into place, the channel through which the pipes 16 pass being subsequently closed by the means described.

It is to be particularly understood that the apparatus is primarily intended for a quick freezing and storage device for frozen foods. The device is so constructed that there is in effect a double seal between the interior of each drawer and the outside for the reason that the front of each drawer seals itself and prevents circulation of air and, in addition to this, the front door provides the first or main seal between the interior and exterior of the cabinet.

When a front door is opened, the cold air does not rush out from the apparatus. Only a very small portion of the dense cold air is spilled and lost. When a drawer is pulled outwardly, it traps or holds the heavy cold air therein as the drawer is imperforate with regard to its bottom and other walls. Obviously the article desired may be removed from the drawer or an article may be placed in the drawer. The warm air that has flowed in behind the drawer when the drawer is pulled out is discharged when the drawer is pushed back into place and the cold air trapped within the drawer is not disturbed. It is to be noted that the evaporator plates 14 constitute means for preventing circulation of air between the spaces adjacent successive drawers. Thereafter the main door is shut, thus completely sealing the apparatus. There is thus the minimum

loss of cold air and the minimum entrance of heated air even when a drawer is pulled outwardly after opening the main door.

Preferably an evaporator unit or plate 14 is positioned above and below each drawer except the lowermost drawer and these evaporator units are spaced from the bottom of the adjacent drawers so as to prevent any chance of freezing and sticking of the drawer to the unit. It has been observed in this particular construction of refrigerating apparatus that the freezing occurs substantially entirely on the lower side of the evaporator units and very little frost forms on the upper side of the evaporator units 14. By having the bottom of the drawers spaced from the adjacent evaporator units, the drawers never freeze to the evaporator units. The imperforate bottoms of the drawers form with the evaporator plates dead air spaces below the bottom of the adjacent drawer and thus substantially prevent circulation of air in such spaces. After an extended test it has been found that the formation of frost on the upper side of the evaporator plates beneath the bottom of the drawers does not occur to any appreciable extent and consequently there is no sticking or freezing of the drawer to the evaporator plates. The frost collects primarily on the under side of the evaporator plates and this side is also out of contact with the next adjacent drawer and does no harm.

It is to be understood that the extent of piping or expansion surface in the successive evaporator units may be altered and may be different one from the other. It is intended that the uppermost drawer shall be the coldest, for instance considerably below zero in order to provide a quick freezing compartment for quickly freezing the material desired to be stored in a frozen state. The successive drawers are preferably arranged to be maintained at slightly higher temperatures, for example from a few degrees below zero to zero. The exact range of temperatures, however, may be varied as desired.

In using the apparatus after quick freezing has been obtained by filling the uppermost drawer with the articles to be frozen, such drawer may be interchanged with some other empty drawer to maintain the articles in a frozen condition and have the empty drawer available for subsequent use where quick freezing of additional articles is desired. These results are readily obtained by making all of the drawers freely interchangeable and maintaining at least one of the drawers, for instance the uppermost one, at a materially lower temperature than the other drawers for quick freezing, the remaining drawers being adapted for the storage of the frozen foods.

If desired, the particular compartment, for example the uppermost one, used for quick freezing may not be provided with a drawer but as shown in Figure 4 may be provided with an auxiliary or inner door 34 hinged about one side edge as indicated at 35 and provided with a spring type or other type of latch indicated generally at 36. The second evaporator unit 14 forms the bottom of such compartment and the uppermost evaporator unit forms the upper wall of such compartment. It has been found that the time required for quick freezing is reduced if a slight circulation of air is maintained. Therefore, it is within the province of this invention to provide a small electric motor driving a fan as indicated at 37 and carried by the auxiliary door 34, as shown in Figure 4. The fan may be operated for

a brief interval to hasten the quick freezing and when not needed, may be cut off.

It is thus possible to replace the uppermost drawer and use the construction shown in Figure 4. This construction is particularly serviceable for a relatively short user as it may be difficult for a short person to look downwardly into or reach downwardly into the uppermost of the drawers for the construction shown in Figure 1. Therefore an auxiliary door 34 as shown in Figure 4 is provided to facilitate the positioning of foods in the quick freeze compartment. Also this construction allows the foods to be quickly frozen, preferably with the foods suitably wrapped, to be positioned directly upon the evaporator unit forming the bottom of such quick freeze compartment.

While the plates 14 have been referred to as evaporator plates, it is to be distinctly understood that any suitable type of refrigerating plates may be used.

It is to be noted particularly with reference to Figures 1 and 3 that the evaporator plates divide the interior of the cabinet into a plurality of separate and distinct compartments and thus preventing circulation of air between the compartments for successive drawers and that the drawers substantially fill their respective compartments and their front faces are in close proximity to the rear face of the door. It is apparent from this that when the door is opened, very little cold air is lost and when a drawer is pulled outwardly, warm air replaces the outwardly drawn drawer and is again expelled when such drawer is pushed backwardly. Thus the minimum of disturbance of cold air within the body of the low temperature cabinet is obtained although free access is provided for each of the drawers. Additionally it is to be noted that each drawer is provided with a front portion which jointly form a substantial second or auxiliary seal in addition to the main seal provided by the door.

It will be seen that a novel low temperature cabinet has been provided by this invention which is so constructed that individual drawers are provided and are so arranged that a double seal is furnished by the drawers themselves and the main door.

It will be seen further that the device may be so arranged that one of the drawers is adapted for quick freezing and the other drawers arranged for the storage of frozen foods. All of the drawers are interchangeable.

Although this invention has been described in considerable detail, it is to be understood that such description is intended as illustrative rather than limiting, as the invention may be variously embodied and is to be interpreted as claimed.

We claim:

1. A low temperature cabinet comprising an inner and an outer casing having thermal insulation therebetween, said cabinet having an open front, a door normally closing said open front and forming a main seal for said cabinet, a plurality of vertically spaced drawers within said cabinet with each drawer having a front wall, the front walls of said drawers being spaced inwardly of said door and forming a second seal for said cabinet, and refrigerating means between said drawers arranged to prevent circulation of air between the spaces adjacent successive drawers.

2. A low temperature cabinet comprising an inner and an outer casing having thermal insulation therebetween, said cabinet having an open

front, a door normally closing said open front and forming a main seal for said cabinet, a plurality of vertically spaced drawers within said cabinet with each drawer having a front wall, the front walls of said drawers being spaced inwardly of said door and forming a second seal for said cabinet, said cabinet having means for preventing the circulation of air between the spaces adjacent successive drawers, and refrigerating means between said drawers, said drawers being out of contact with said refrigerating means.

3. A low temperature cabinet comprising an inner and an outer casing having thermal insulation therebetween, said cabinet having an open front, a door normally closing said open front and forming a main seal for said cabinet, a plurality of drawers within said cabinet with each drawer having a front wall, the front walls of said drawers being spaced inwardly of said door and forming a second seal for said cabinet, and refrigerating means adjacent said drawers, said cabinet including means for preventing circulation of air between the spaces adjacent successive drawers, said drawers having imperforate side, end and bottom walls, whereby when a drawer is pulled outwardly the chilled dense air in such drawer is retained within the drawer.

4. A low temperature cabinet having an open front, a door normally closing said open front, a plurality of spaced, horizontally arranged refrigerating plates dividing said cabinet into a series of vertically arranged compartments, means for supplying a refrigerant to said refrigerating plates, and drawers in said compartments, said refrigerating plates substantially preventing circ-

ulation of air between the spaces adjacent successive drawers, whereby when a drawer is withdrawn only a small amount of cold air is lost.

5. A low temperature cabinet having an open front, a door normally closing said open front and forming a main seal, a plurality of spaced, horizontally arranged refrigerating plates dividing said cabinet into a series of vertically arranged compartments, means for supplying a refrigerant to said refrigerating plates, and drawers in said compartments, said drawers having front walls close to cold door and forming a second seal, said refrigerating plates substantially preventing circulation of air between the spaces adjacent successive drawers, whereby when the door is opened and a drawer withdrawn only a small amount of cold air is lost.

6. A low temperature cabinet comprising an inner and an outer casing having thermal insulation therebetween, said cabinet having an open front, a door normally closing said open front and forming a main seal for said cabinet, a plurality of vertically spaced drawers within said cabinet with each drawer having a front wall, the front walls of said drawers being spaced inwardly of said door and forming a second seal for said cabinet, said drawers having imperforate bottoms, and refrigerating means including evaporator plates located between successive drawers and spaced from adjacent drawers and forming with the bottoms of adjacent drawers dead air spaces substantially free from circulation, whereby freezing of the drawers to adjacent evaporator plates is prevented.

ROBERT D. WEST,
WILHELM U. VELTON.
